(57) CLAIM

The ornamental design for a toothbrush containing a combination of elastomeric and filament tufts, as shown and described.

DESCRIPTION

FIG. 1 is a front, right side perspective view of a toothbrush containing a combination of elastomeric and filament tufts of my new design as seen from the top thereof;

FIG. 2 is a front elevation view thereof;

FIG. 3 is a back elevation view thereof;

FIG. 4 is a left side elevation view thereof, the right side elevation being a mirror image of the right side elevation as shown herein in FIG. 4;

FIG. 5 is a top view thereof; and,

FIG. 6 is a bottom view thereof.
